UNITED STATES PATENT OFFICE.

HERMAN L. PERLISH, OF PHILADELPHIA, PENNSYLVANIA.

DESIGN FOR A SAFETY RAZOR.

Application filed August 12, 1925. Serial No. 14,400. Term of patent 14 years.

To all whom it may concern:

Be it known that I, HERMAN L. PERLISH, a citizen of the United States, residing at Philadelphia, in the county of Philadelphia and State of Pennsylvania, have invented a new, original, and ornamental Design for a Safety Razor, of which the following is a specification, reference being had to the accompanying drawing, forming part thereof.

Figure 1 is a perspective view looking toward the underside of a safety razor showing my new design.

Figure 2 is also a perspective view looking toward the upper side thereof.

I claim:

The ornamental design for a safety razor, as shown.

HERMAN L. PERLISH.
